CLAIM

The ornamental design for a medicine cabinet, as shown and described.

DESCRIPTION

FIG. 1 is a front perspective view of a medicine cabinet according to a first embodiment of the present invention; FIG. 2 is a front view of the medicine cabinet according to the first embodiment of the present invention;

FIG. 3 is an enlargement taken from FIG. 1 as indicated; FIG. 4 is an enlarged top section view taken from FIG. 2 as indicated;

FIG. 5 is an enlarged left side section view taken from FIG. 2 as indicated;

FIG. 6 is an enlarged right side section view taken from FIG. 2 as indicated;

FIG. 7 is a front view of FIG. 4 thereof;

FIG. 8 is a bottom view of FIG. 4 thereof;

FIG. 9 is a front perspective view of a medicine cabinet according to a second embodiment of the present invention; FIG. 10 is a front view of the medicine cabinet according to the second embodiment of the present invention;

FIG. 11 is an enlargement taken from FIG. 9 as indicated; FIG. 12 is an enlarged top section view taken from FIG. 10 as indicated;

FIG. 13 is an enlarged left side section view taken from FIG. 10 as indicated;

FIG. 14 is an enlarged right side section view taken from FIG. 10 as indicated;

FIG. 15 is a front view of FIG. 12 thereof; and,

FIG. 16 is a bottom view of FIG. 12 thereof.

Portions of the medicine cabinet shown in broken lines are not part of the claimed design. The rear view and top view of the medicine cabinet are not part of the claimed design.

1 Claim, 6 Drawing Sheets
